UNITED STATES PATENT OFFICE.

JOHN E. MEEK, OF NEW YORK, N. Y.

DESIGN FOR AN ELECTRIC HEATER.

SPECIFICATION forming part of Design No. 30,598, dated April 18, 1899.

Application filed July 15, 1898. Serial No. 686,046. Term of patent 14 years.

To all whom it may concern:

Be it known that I, JOHN EMORY MEEK, a citizen of the United States, residing in the city, county, and State of New York, have invented and produced a new and original Design for Electric Heaters, of which the following is a specification, reference being had to the accompanying drawings for a full description thereof.

10 Figure 1 is a side elevation of my heater, showing my new design. Fig. 2 is a sectional view taken on line 2 2 of Fig. 1.

As shown in the drawings, the leading or material feature of my design consists of a 15 series of rods A' A², &c., arranged in a circular form about one of them, as A, and supported at each end in circular heads B B'. About each of these rods is arranged a spiral coil of wire C C', &c. The wire and rod in 20 each case should be of different colors—that is to say, if the rods are of dark color the wire should be of bright color or highly polished.

Then the wire spiral will show plainly in contrast to the dark background of the rod. The whole is then surrounded by an open-work 25 casing D, supported also by the heads B B'. Through the openings E and E' in this casing the coils C and rods A can be plainly seen. The openings E E', &c., are oblong in shape, with their greater dimensions parallel to the 30 rods A A'.

The whole heater is supported in a horizontal position on two standards F F', as shown.

Having therefore described my invention, what I claim as new, and desire to protect by 35 Letters Patent, is—

The design for an electric heater, as herein shown and described.

In testimony whereof I have hereunto set my hand this 16th day of June, 1898.

JOHN E. MEEK.
